UNITED STATES PATENT OFFICE

2,470,375

VENTILATOR

Alfred L. Schwartzberg, Shreveport, La.

Application February 13, 1946, Serial No. 647,333

13 Claims. (Cl. 98—118)

1

This invention relates to improvements in ventilators, and more particularly to a box or housing type ventilator adapted to be positioned in a window opening to permit fresh air to enter a building without causing a draft.

An object of the invention is to provide an improved window ventilator in the form of a box or casing having a series of openings and baffle plates in its opposite sides, and means on the outside of said ventilator to partially or entirely cut off the air passing through it.

Another object of the invention is to provide an improved window ventilator with air-directing baffle plates or louvers formed in its opposite sides to permit air to pass therethrough without causing a draft, and a slidably, resiliently supported closure means for controlling the amount of air passing through said ventilator.

A further object of the invention is to provide an improved ventilator for window openings which will be highly efficient in operation, and relatively inexpensive to manufacture and produce.

Other objects will appear as the description proceeds.

In the accompanying drawings which form a part of this application,

Figure 1 is a front elevation of the improved double-section ventilator positioned in a transom opening over a pair of doors;

Figure 2 is a perspective view of a single ventilator unit;

Figure 3 is a sectional view taken on the line 3—3 of Figure 1;

Figure 4 is a sectional view taken on the line 4—4 of Figure 1; and

Figure 5 is a perspective view of a stick operator for adjusting the ventilator when placed above a door opening out of reach for manual operation.

Like characters of reference are used throughout the following specification and the accompanying drawings to designate corresponding parts.

In carrying out the invention, it will be understood that the improved ventilator may include one or more units which will be placed in any desired opening, for example, in a window opening or in a transom opening over a doorway.

Each unit comprises a substantially rectangular casing generally denoted by the reference numeral 1, and having a top 2, a bottom 3, a front or weather side 4, and a rear or inside 5.

In Figure 1, there is illustrated a door frame 6

2

in which the doors 7 are hinged at 8, and an overhead transom frame 9, in which frame a double unit, or two separate units are positioned and held therein in any desired manner.

Each unit is formed with spaced series of openings 10 and 11 spaced parallel, upwardly extending baffle plates or louvers 11, in its outside and inside wall portions 12 and 13, respectively.

Guide channels 14 and 15 are formed at the opposite ends of the inside wall 13, and inwardly thereof to provide the U-shaped track for slidably receiving the closure plate 16, which has two elongated openings or apertures 17 and 18 formed throughout, so arranged that when the plate 16 is in its lowermost position, the body of the plate will close off the inlet louvers 11 in the said inside wall 13. However, when the plate 16 is in its raised or uppermost position, the apertures 17 and 18 will register with the louvers 11 to permit outside air to pass through the ventilator and into the inside of the house or room.

The aligned vertical guide slots 17 and 18 are formed through the sliding closure plate 16, and are adapted to receive the thumb screws 19 and 20, on which the coil springs 21 and 22 are mounted, said screws 19 and 20 being engageable with and supported by the inside wall 13 of the ventilator casing 1. By turning down on the thumb screws 19 and 20, the desired resilient tension may be secured for holding the closure plate 16 in the desired adjusted position.

The closure plate operating finger 23 is secured to the lower edge of the closure plate 16 and extends forwardly thereof, so that the same may be readily grasped, and the said closure plate 16 raised to open the ventilator, or lowered to close the ventilator.

An elongated closure-operating stick is provided when the ventilator unit is placed too high to reach for manual operation. Said stick comprises a handle 24 and a forked head 25 having outwardly extending parallel finger-engaging arms 26 and 27, which may be placed over the finger 23 to raise and lower the closure plate 16.

Since the louvers 11 are inclined upwardly, there will be no direct draft produced when the ventilator is opened.

While the preferred form of the instant invention has been illustrated and described, it will be understood that it is not intended to limit the scope of the invention thereto, as many minor changes in details of construction may be resorted to without departure from the spirit of

the invention.

Having thus described my invention, what I claim as new and desire to secure by Letters Patent of the United States is:

1. In combination with a structure having an opening, a ventilator adapted to be supported in said opening including a casing having an inner and outer side wall, a closed top, bottom and end walls, said side walls having vertically spaced elongated horizontal openings, each of said openings being provided with an upwardly and inwardly directed vane, vertical guide channels at the ends of said casing on the room side thereof, a closure plate having vertically spaced elongated horizontal apertures formed therethrough slidably supported in said guide channels for controlling the flow of air through said louvers, said closure plate being formed with vertically aligned elongated guide slots, headed supporting members secured to the adjacent inside wall of said casing and extending through said slots, and an inwardly extending closure plate operating tab on the bottom of said closure plate.

2. In combination with a structure having an opening, a ventilator adapted to be supported in said opening including a casing having closed top, bottom and end walls, vertically spaced elongated horizontal openings in the inner and outer walls of said casing louvers extending upwardly and inwardly from the inner and outer walls adjacent the openings, vertical guide channels at the ends of said casing on the room side thereof, a closure plate having vertically spaced elongated horizontal openings formed therethrough slidably supported in said guide channels for controlling the flow of air through said louvers, headed supporting member secured to the adjacent inside wall of said casing and extending outwardly therefrom, said closure plate being formed with a pair of vertically aligned elongated slots slidably disposed on the members, adjustable resilient ten-

sioning means on said members for resiliently supporting said closure plate in any desired adjusted position, and an inwardly extending closure plate operating tab on the bottom of said closure plate for moving said plate vertically on the members.

3. In combination with a structure having an opening, a ventilator adapted to be supported in said opening and including a casing having a closed top, bottom and end walls, vertically spaced elongated horizontal openings in the inner and outer walls of said casing, vertical guide channels disposed at the ends of said casing on the room side thereof, a closure plate having vertically spaced elongated horizontal apertures formed therethrough slidably supported in said guide channels for controlling the flow of air through said louvers, a pair of adjusting and supporting lugs secured to the inside wall of said casing, resilient tensioning means associated with said lugs, vertically aligned guide slots formed in said closure plate and slidably disposed on said supporting lugs, and an inwardly extending operating tab on the bottom of said closure plate for moving said plate vertically on the lugs.

ALTER L. SCHWARTZBERG.
